(57) **CLAIM**

The ornamental design for a toy car, as shown and described.

DESCRIPTION

FIG. 1 is a front elevational view of a toy car showing my new design;

FIG. 2 is a rear elevational view thereof;

FIG. 3 is a left side elevational view thereof;

FIG. 4 is a right side elevational view thereof;

FIG. 5 is a bottom view thereof;

FIG. 6 is a top view thereof;

FIG. 7 is a right front perspective view thereof; and,

FIG. 8 is a left side rear perspective view thereof.

That portion of the FIGS. shown in broken lines form no part of the claimed design.
